UNITED STATES PATENT OFFICE.

HARRY BAYER, OF POUGHKEEPSIE, NEW YORK, ASSIGNOR TO KOTH-BAYER, OF POUGHKEEPSIE, NEW YORK, A COPARTNERSHIP.

BUSHING FOR PIANO TUNING-PINS.

1,264,140.

Specification of Letters Patent. Patented Apr. 30, 1918.

Application filed May 19, 1915. Serial No. 29,122.

To all whom it may concern:

Be it known that I, HARRY BAYER, a citizen of the United States, residing at Poughkeepsie, in the county of Dutchess and State 5 of New York, have invented certain new and useful Improvements in Bushings for Piano Tuning-Pins, of which the following is a specification, reference being had thereto in the accompanying drawing.

10 My invention relates to improvements in pianos, and more particularly has reference to means for securing the piano wires or strings in position.

Referring to the accompanying drawings, 15 Figure 1 illustrates a broken section of a portion of a piano embodying an application of my invention. Fig. 2 is a cross section on the line 2—2 of Fig. 1. Fig. 3 is a perspective view of one of my metallic bushings, and Fig. 4 a perspective view of one 20 of the usual form of wooden bushings.

5 indicates the usual iron frame or string plate over which the strings are secured, and 6 the tuning pins to which the strings 25 are secured. 7 indicates the usual wrist plank to which the iron plate 5 is secured and into which the pins 6 penetrate, said pins being provided with the usual fine thread indicated by the reference character 30 8. 9 indicates the usual form of wooden bushing shown to better advantage in Fig. 4 which usually fits into the hole in the iron plate 5 and through which pins such as 6 are secured.

35 It has been found that by forming a metallic bushing such as 10 substantially as shown in Fig. 3 with an outer flange or rim such as 11, and by fitting the same within the hole in the iron plate 5 before applying 40 the wooden bushing such as 9 that a better construction is obtained. These metallic bushings are preferably formed out of sheet brass of such a size that the wooden bushings snugly and tightly fit therein and so 45 that the metallic bushings snugly and

tightly engage the hole in the iron plate 5. When the pin 6 has been secured therein as shown in Fig. 2 the likelihood of the same coming loose is actually reduced to a minimum, and the wooden bushing 9 is better secured in place. The arrangement also contributes to a more finished appearance as well as to the quality of the instrument and durability of the same. The strings 12 are of course passed through the pins 6 and 55 wound thereupon in the usual manner.

Of course it will be understood that various modifications may be made without departing from the spirit of the invention as claimed. 60

I claim:

1. In combination with the string plate and tuning pins of a piano, a bushing through which each pin passes, and a bushing between said first mentioned bushing 65 and the walls of the hole in said plate within which said bushing is seated.

2. In combination with the string plate and tuning pins of a piano, a bushing through which each pin passes and a metallic bushing between said first mentioned bushing and the walls of the hole in said plate within which said metallic bushing is seated, said metallic bushing having a flange extending over the edge of the wall 75 in said plate.

3. Bushings for the tuning pins of a piano comprising a straight walled tubular wooden member through which the pin passes and an outer tubular metallic member within 80 which said tubular wooden member is seated, said outer tubular member having an outwardly extending flange.

In testimony whereof I hereunto affix my signature in the presence of two witnesses. 85

HARRY BAYER.

Witnesses:

LOUISE ENDERLE,
THOMAS A. HILL.
